Merchant and Pieters

UNITED STATES PATENT OFFICE.

RAY G. PIETERS, OF CHICAGO, ILLINOIS, ASSIGNOR OF ONE-HALF TO ALBERT N. TERRY, OF MINNEAPOLIS, MINNESOTA.

STEAM APPLICATOR FOR WALL-PAPER-removing APPARATUS.

Application filed June 21, 1926. Serial No. 117,397.

My present invention has for its object to provide a highly efficient steam applicator for wall paper removing apparatus, and to this end it consists of the novel devices and combinations of devices hereinafter described and defined in the claims.

In the accompanying drawings, which illustrate the invention, like characters indicate like parts throughout the several views.

10 Referring to the drawings:

Fig. 1 is a perspective face view of the applicator;

15 Fig. 2 is a perspective back view of the same, with the handle shown in a different position by means of broken lines;

Fig. 3 is a fragmentary detail view in transverse section taken on the line 3—3 of Fig. 1 on an enlarged scale;

20 Fig. 4 is a fragmentary detail view in longitudinal section taken on the line 4—4 of Fig. 1, on an enlarged scale;

Fig. 5 is a fragmentary detail view partly in side elevation and partly in section taken on the line 5—5 of Fig. 2, on an enlarged 25 scale; and

Fig. 6 is a fragmentary detail view in section taken on the line 6—6 of Fig. 1, on an enlarged scale;

The numeral 7 indicates a sheet metal casing in the form of a shallow pan, the sides of which at the open face of said casing have a relatively deep endless channel 8 in which is mounted an endless combined insulating and joint strip 9 of rubber or other suitable 35 material. Said channel 8 is outside of the sides of the casing 7 and the strap 9 projects outwardly from said channels. A handle 10 is secured to the back of the casing 7 by an L-shaped bracket 11 the perpendicular

40 member of which comprises two overlapping sections connected by a slot and nut-equipped bolt connection 12 arranged to permit lateral swinging movement of the handle 10 parallel to the back of the casing 7. Said sections 45 of the bracket 11 are held aligned by a notch and lug connection 13. The members of the connection 13 are held interlocked by the nut-equipped bolt of the connection 12, as shown by full lines in Figs. 2 and 5.

50 Within the casing 7 is a transverse hollow reinforcing rib 14 secured to the back of said casing with its ends secured to and closed by the respective sides of said casing. This rib 14 is located midway between the 55 top and bottom of the casing 7 and affords a

steam distributing chamber 15, and it will be noted that the depth of said rib is less than that of the sides of the casing 7. A corrugated metal sheet 16 is secured in the casing 7 on each side of the rib 14 with its 60 corrugations extending longitudinally of said casing and transversely of said rib. Each sheet 16 completely fills the respective section of the casing 7 in which it is secured.

The inner ends of the corrugations in the 65 sheets 16 are closed by the sides of the rib 14 and the outer ends thereof are secured to and closed by the respective sides of the casing 7. The inner ridges of the corrugations in the sheets 16 rest on the back of the casing 70 7 and are secured thereto. The corrugations closed by the back of the casing 7 afford laterals 17 with which the steam distributing chamber 15 has communication through holes 18 formed in the sides of the rib 14. 75 In the outer ridges of the corrugations in the sheets 16 are a multiplicity of longitudinally spaced orifices 19 for the discharge of steam from the laterals 17 through the open face of the casing 7. The depth of the 80 laterals 17 is considerably less than that of the steam distributing chamber 15.

A steam pipe 20 is laid in the central outer 85 corrugation in the lower sheet 16 and extends through holes in the lower side of the casing 7 and the lower side of the rib 14 and is rigidly secured thereto. This steam pipe 20 extends below the bottom of the casing 7 to afford a steam hose connection leading from a steam generating apparatus, not 90 shown.

In the lower end of the casing 7 is a shallow trough 21 for the collection of condensed steam which takes place outside of the rib 14 and corrugated sheets 16.

95 Steam conveyed from the generating apparatus, not shown, to the distributing chamber 15 from the steam pipe 20 enters the laterals 17 from said chamber through the holes 18 and escapes through the orifices 19 in jets directed through the open face of the casing 7. In removing wall paper from a wall the applicator is held by the handle 10 with its open face turned toward the wall and with its combined insulating and joint strip 9 pressed against said wall to close the casing 7 and confine the steam discharged from the orifices 19. The jets of live steam from the laterals 17 are directed against the wall paper and upon striking the same are 100 105 110

condensed and quickly penetrate the paper and loosen the same from the wall. The dead steam in the casing 7 also materially assists in loosening the paper from the wall.

5 The arrangement of the laterals 17 and their orifices 19 is such that the steam is evenly directed over the wall paper so that the entire piece within the field of the casing 7 is simultaneously loosened. The strip 10 9 is flexible and seals the joint between the applicator and the wall, and it also acts as an insulator to protect the woodwork from the hot sides of the casing 7 and further prevents the escape of steam against the wood- 15 work.

The rib 14 and corrugated sheets 16 greatly strengthen the apparatus so that the same may be made from relatively light material, and the applicator will not budge or 20 warp under steam pressure in the distributing chamber and laterals 17. Due to the converging lines of the laterals 17 there is no chance for the collection of condensation therein and said condensation will be blown 25 from the laterals 17 through the orifices 19 and any condensation that takes place outside of the rib 14 and corrugated sheets 16 will be collected in the trough 21. By keeping the applicator free from condensed 30 steam, no extra weight is added thereto, so that the same may be easily handled by the operator. The purpose of making the handle adjustable is to permit said handle to be turned into a position as indicated by dotted lines in Fig. 2 so that the applicator may 35 be used back of a radiator or the like.

What I claim is:

1. An applicator of the kind described comprising a casing, a hollow reinforcing 40 rib affording a steam distributing chamber, a connection for a steam supply member on said chamber, a corrugated sheet in said casing having its corrugations closed by the back thereof to afford lateral steam conduits 45 each having one end in communication with said chamber and the other end closed, said conduits having a plurality of orifices for the escape of steam.

2. An applicator of the kind described comprising a casing, an intermediate hollow 50 reinforcing rib affording a steam distributing chamber, a connection for a steam supply member on said chamber, and a corrugated sheet in the casing on each side of said rib, the corrugations in said sheets being extended transversely of said rib and closed by the back of the casing to afford lateral steam conduits, the inner ends of which have communication with said rib and the outer ends of which are closed, said conduits having a plurality of orifices for the escape of steam.

3. The structure defined in claim 2 in which said connection is in the form of a pipe which extends through an opening in 65 one of the sides of the casing longitudinally between certain of said corrugations and has its inner end secured to said rib.

4. An applicator of the kind described comprising a casing having an open face 70 adapted to be placed against a wall, a steam distributing chamber in the casing extending the full length thereof, and closely positioned lateral steam conduits leading from the distributing chamber and completely 75 filling the casing, said chamber having a connection for a steam supply member, and said conduits having a plurality of orifices for the escape of steam.

5. An applicator of the kind described 80 comprising a casing having an open face adapted to be placed against a wall, a steam distributing chamber in the casing extending the full length thereof and provided 85 with a connection for a steam supply member, and a corrugated sheet in said casing having its corrugations longitudinally closed by the back thereof to form closely positioned parallel lateral steam conduits, one of 90 the ends of said conduits being in communication with said chamber and the other ends being closed, said conduits completely filling the chamber and having a plurality of orifices for the escape of steam.

In testimony whereof I affix my signature.
RAY G. PIETERS.
